[57] CLAIM

The ornamental design for a nesting handtruck, as shown and described.

DESCRIPTION

FIG. 1 is a perspective of nesting handtruck with an additional handtruck indicated in phantom, showing the nesting arrangement;

FIG. 2 is a top plan view;

FIG. 3 is a side elevation, the opposite side being a mirror image;

FIG. 4 is a front elevation; and,

FIG. 5 is a rear elevation.
